FABRIC TRIMMING AND THREAD LAYING
MECHANISM FOR SEWING MACHINESFrederick F. Zeier, Chicago, and August H. Stieg,
Des Plaines, Ill., assignors to Union Special
Machine Company, Chicago, Ill., a corpora-
tion of Illinois

Application April 10, 1931. Serial No. 529,244

11 Claims. (Cl. 112—122)

The invention relates to new and useful improvements in sewing machines, and more particularly to a sewing machine provided with means for trimming the upturned edge portions 5 of fabric sections and subsequently joining and covering the edge portions by stitching the threads.

An object of the invention is to provide a machine of the above type having a presser foot 10 for directing the upturned edge portions, which presser foot supports the stationary member of horizontally disposed trimming devices with a single bracket having means adapted to engage the shank portion of the presser foot for positively holding said presser foot against any turning movement axially of the supporting bar therefor in either direction during the trimming of the fabric sections.

A further object of the invention is to provide a machine of the above type, wherein the movable trimming device and the thread laying members are actuated from a sleeve surrounding the presser bar, with means extending throughout a considerable length of the actuating 25 sleeve for supporting the same, whereby any clamping or binding action is prevented during the actuation of said sleeve.

These and other objects will in part be obvious and will in part be hereinafter more fully disclosed.

In the drawings, which show by way of illustration one embodiment of the invention:—

Figure 1 is a view of a portion of a machine embodying the improvements, the view being 35 taken from the side of the needle head.

Figure 2 is a view showing the needle head and supporting member therefor in vertical section.

Figure 3 is an enlarged side view of the presser foot and the parts associated therewith.

Figure 4 is a plan view of the parts shown in Figure 3.

Figure 5 is a horizontal sectional view on the line 5—5 of Figure 3, also showing in section the bracket associated with the presser foot and 45 maintaining the parts in alinement.

Figure 6 is a perspective view of the bracket carried by the lower end of the needle head operating to hold the presser foot from lateral movement on its supporting bar.

The invention includes a sewing machine having trimming devices disposed for relative movement in a horizontal plane for trimming the upturned edge portions of fabric sections which are to be joined and covered by stitching. The machine is also provided with a presser foot having

a channel or guiding slot leading from the forward end thereof past the trimming devices for directing the upturned edge portions, and for downfolding their edge portions after they are trimmed. Associated with the presser foot is a finger carried by the work support which aids in directing the edge portions to the trimmer and for turning down the edge portions. The machine includes also a plurality of needles, preferably three, so that the edge portions, after they are 60 trimmed and turned down in lapped relation, will be penetrated by the center needle while the outer needles pass outside of the cut edges. The machine also includes a cover thread laying mechanism for laying a cover thread so that it will be 65 stitched to the fabric sections and will cover the raw edge of the material on the upper face of the fabric as well as join the outer rows of needle thread loops. The particular new feature of the present invention is in the means for supporting 70 and operating the movable trimming blade and the cover thread laying devices, and also in the manner of supporting the presser foot so as to prevent said presser foot from lateral movement during the trimming operation and also during 75 the laying of the covering thread.

Referring more in detail to the drawings, the invention is shown as applied to a sewing machine having a supporting standard 1 carrying a bracket 2 at the upper outer edge of which is 80 mounted a horizontal member 3, in which the main actuating shaft 4 is located. The upper horizontal member 3 carries a needle head 5 which is secured thereto by suitable bolts 6 and 7. The bolt 6 is passed through a lug 8 in the 85 upper horizontal member and is threaded into the upper frame member of the needle head 5. The bolt 7 passes through a lug 9 carried by the needle head and is threaded into the lower frame portion of the upper horizontal member 3. There 90 are other bolts of a similar character, and thus it is that the needle head is firmly but removably attached to the main supporting frame of the machine. The upper horizontal member 3 carries a depending member 10 at the lower end of 95 which is suspended a work arm 11. The outer end 12 of the work arm terminates beneath the needle head 5. This machine frame referred to above is of the character shown and described in the patent granted to Norman V. Christensen and 100 Harold J. LeVesconte December 24, 1929, No. 1,741,095.

Mounted in the needle head is a needle bar 13 carrying three needles 14, 15 and 16. The needle bar is reciprocated by means of a needle lever 17 110

mounted on a shaft 18 carried by the horizontal member 3. This needle lever is connected by a link 19 to a lug 20 which is fixed to a sleeve carried by the needle bar. The shaft 4 is provided with a crank 21 with which a link 22 cooperates. This link is connected to a ball stud 23 at its outer end, which ball stud is carried by the needle lever 17. As the main shaft rotates the needle bar will be reciprocated by the oscillations of the needle lever 17.

Cooperating with the needle beneath the work support is a series of loopers, one for each needle. One of these loopers is indicated at 24. The looper mechanism and the parts directly associated therewith form no part of the present invention, but are shown, described and claimed in co-pending application Serial No. 529,241, filed April 10, 1931, by Frederick F. Zeier.

The material is supported on the work arm 11 which is comparatively small in cross section so that small tubular articles may be stitched on the machine. The material is fed off from the end of the work support by a feed mechanism including a main feed dog 25 and an auxiliary feed dog 26. The auxiliary feed dog is located in front of the needle and may be given a differential movement relative to the main feed dog so that the machine is particularly adapted for stitching and joining the edge portions of knitted fabrics. The material is held on the work support by a presser foot 27 which is carried by a presser bar 28. The presser bar 28 carries an operating sleeve 29 which oscillates the trimmer and the cover thread laying mechanism. This operating sleeve 29 is mounted in a fixed sleeve bearing 30 carried by the needle thread. This sleeve bearing 30 forms one of the supporting bearings for the presser bar. At the upper end of the presser bar is mounted a sleeve bearing 31 carried by the upper frame member of the needle head 5. Fixed to the presser bar above the operating sleeve 29 is a collar 32. Said collar is secured to the presser bar by screws 33, 33. The collar is provided with projecting arms 34 and 35. These arms are preferably formed integral with the sleeve. The arms straddle a guide bar 36 which is mounted in the upper member of the needle head 5. Said guide bar has the sides thereof slabbed or flattened as indicated at 37 and the arms bear respectively upon the flattened side portions which are at the opposite sides of the guide bar 36. This provides one way of holding the presser bar from turning in its bearings, and at the same time permitting the presser bar to be raised and lowered in its bearings.

This same collar 32 carries a rearwardly projecting lug 38. A flat leaf spring 39^a bears on this lug and serves as a means for yieldingly forcing the presser bar downward and the presser foot against the material on the work support. The presser bar may be raised at will through the aid of a rock lever 39 which is provided with an arm 40 extending underneath the rounded lower face of the lug 38. A link 41 is pivoted at 42 to this rock lever 39, and when this link is pulled upon the presser foot will be raised.

As a further means for preventing the presser bar from turning in its bearings a bracket 43 is provided, which is attached to the underface of the needle head by bolts 44, 44 passing through a supporting base member 45 with which the bracket 43 is integrally formed. Said bracket has a flat guide face 46 and also an arm 47 which projects forwardly and is provided with a second flat bearing face 48. The presser foot includes a

shank portion 49. The shank portion 49 carries an integral sleeve portion 50 which receives the lower end of the presser bar 28. A set screw 51 serves as a means for attaching the shank of the presser foot to the presser bar. The shank of the presser foot carries a rearwardly projecting arm 52 which engages the flat face 46 of the bracket 43. The shank of the presser foot is also provided with a laterally projecting portion 53 in front of the presser bar which bears against the flat portion 48 of the bracket 43. The shank of the presser foot, although it makes engagement with this bracket 43 and is prevented thereby from any oscillations or turning movements on or with the presser bar, nevertheless is free to move vertically maintaining its contact with this bracket 43. From the above it will be apparent that the presser foot will be held from any turning movements and in alignment with the feed and stitching mechanism, not only by the guide bar 36 with which the guide arms 34 and 35 cooperate, but also by this bracket 43 which has a two-point contact with the presser foot shank, one in front of the presser bar and the other in the rear thereof. The arm 52 with its contact with the flat face 46 prevents the presser foot from any clockwise movements about the axis of the presser bar, and the laterally projecting portion 53 of the presser foot through its contact with the flat face 48 prevents any counter-clockwise turning movements of the shank of the presser foot about the axis of the presser bar.

It will be noted that this bracket 43 which engages the shank of the presser foot and prevents any turning movements thereof, is mounted on the under face of the needle head; therefore, it does not, in any way, obstruct the handling of the material which is being stitched. Furthermore, the openings 44^a in the bracket 43 through which the bolts 44 pass, are of larger diameter than the shanks of the bolts. This permits the bracket to be shifted laterally and secured in the desired position in order to properly align the presser foot with the feed and stitching elements. The two arms which engage the presser foot shank are integrally formed with the one single bracket structure, and are, therefore, rigidly fixed in a predetermined position relative to each other. When one is shifted by a movement of the bracket, the other is likewise shifted, and therefore, for all shifted or set positions of the bracket, the arms will be properly positioned to make contact with the presser foot shank and prevent movements thereof in either direction. Furthermore, the bolt holes through the bracket are so timed that the bracket may be given a shift in any direction in order to take up wear between either of the arms carried thereby and the portion of the presser foot with which it cooperates.

The presser foot 27 is provided with a channel or slot 54 which leads in from the front end of the presser foot and serves as a means for guiding upturned edge portions to the trimming mechanism. The trimming mechanism as illustrated includes a fixed trimming blade 55 and a movable trimming blade 56. These trimming blades are mounted for relative movement in a horizontal plane so as to trim the upturned edge portion. The movable blade is provided with a projecting finger 57 which overlies the stationary trimming blade. On the work support is a rib 58 which extends into the channel 54 and aids in directing the edge portions in an upturned position for trimming, and also aids in the turning down of the edge portions after they are trimmed.

This rib may be retracted to allow a cross seam to pass beneath the presser foot. The presser foot in many of its details is similar to that shown, described and claimed in the application of 5 Riviere and Rubel, filed September 12, 1928, Serial No. 305,435. The presser foot contains yielding devices for engaging the fabric sections being stitched. The construction of the foot portion of the presser foot forms no part of the present 10 invention, but is shown, described and claimed in a co-pending application Serial No. 539,350, filed April 15, 1931, by C. F. Rubel. It may be stated briefly that these yielding devices include a flat rigid member 59 carried by posts 60, 61. The post 15 61 carries a cross limiting bar 62. This post is placed in a slot 63 in the presser foot. The post 60 extends up through the foot and a flat spring 64 bears thereon yieldingly forcing the said foot portion downward. A spring 65 bears on the 20 front end of the upturned portion of the rigid member 59. There is a second member 66 which is similar in construction to the member 59, and this member is carried by posts, one of which is shown at 67, which is likewise provided with a 25 cross bar 62 and a spring 68 bearing on the extreme forward end of the member 66 yieldingly forces the member downwardly. There is a similar post at the rear of the member 66 and a leaf spring bears thereon to yieldingly force the same 30 downward. The post 67 is mounted in a slot 69 in the presser foot. In the rear of the members 59 and 66, which can yield independently and simultaneously, is a yielding member 70 carried by a shank portion extending upwardly into the shank 35 of the presser foot. A spring housed within the shank normally forces this member 70 in a downward direction.

The trimming blade 55 is mounted in the presser foot and is held in place by a clamping screw 71. The movable trimming blade 56 is clamped to an arm 72 by screws 73, 73. The arm 72 extends rearwardly and upwardly and is formed as an integral part of the collar member 74. This collar member 74 is rigidly clamped to the 40 lower end of the operating sleeve 29. A bolt 75 passing through arms of this collar member 74 serves as a means for clamping the same to the sleeve 29. The operating sleeve 29 above the bearing sleeve 30 carries a collar 76. Said collar 76 is clamped to the sleeve by means of a screw 77. Said collar carries a rearwardly projecting arm in which a ball stud 78 is secured. Attached to the ball stud 78 is an eccentric strap 79 which cooperates with an eccentric 80 on the 45 main actuating shaft 4. Thus it is that the operating sleeve 29 is oscillated and imparts through the arm 72, supporting the movable trimming blade 56, oscillations to said trimming blade. The cover thread for covering the upper face of the fabric sections between the lines of stitching is directed to a cover thread guiding member 81. There is an eye 82 at the outer end of this member through which the covering thread passes. This member 81 is carried by the shaft 50 83 mounted for oscillation in a bearing sleeve formed as an integral part of a presser foot shank 49. This sleeve is located very close to the laterally projecting portions carrying the smooth face 53, with which the arm 47 of the bracket 55 makes contact. The shaft 83 at its upper end carries an arm 84 to which a link 85 is pivoted at 86. An arm 87 is pivoted at 88 to this link 85. The arm 87 is secured to the upper end of a shaft 89 mounted for oscillations in a sleeve bearing 90 formed as a part of the presser foot shank 49.

Said arm 87 has a laterally projecting portion 91 to which a link 92 is pivoted at 93. The other end of this link is pivoted at 94 to an arm 95 formed as a rigid part of the operating sleeve 29. The sleeve 29 extends all the way down to 80 the upper face of the shank of the presser foot, while the presser bar 28 extends down through the sleeve into the shank of the presser foot and is secured therein by the set screw 51. When the operating sleeve 29 is oscillated it will, through the arm 95, impart oscillations to the arm 87, and the arm 87 through the link 85 will in turn impart oscillations to the cover thread guiding mechanism 81.

Associated with the cover thread guide 81, which has a movement substantially parallel with the line of feed, there is a cover thread laying hook indicated at 96 which engages the cover thread and forms it into a loop. This cover thread laying hook is secured to the lower end of the shaft 89 so that when the shaft 89 oscillates the hook will oscillate, and it moves in a direction approaching a line at right angles to the line of feed. This cover thread laying mechanism, so far as the laying of the threads is concerned, operates in 100 the usual manner, and further description thereof is not thought necessary. The particular feature of the present invention resides in the devices which operate the cover thread guide and the hook member above described. These parts 105 are oscillated from a single connection to the operating sleeve 29. The operating sleeve 29 is mounted in a bearing sleeve which extends throughout a greater portion of the length of the sleeve and from a point adjacent the arm which 110 carries the trimming blade to a point adjacent the collar which oscillates the sleeve. There is, however, sufficient space left so as to permit this operating sleeve to be raised and lowered with the raising and lowering of the presser foot. The 115 presser foot shank is mounted so that the shearing strain of the horizontally moving trimming blade is resisted not only by the arms 34 and 35, at the upper end of the presser bar, but also by the arm 52 which is a rigid part of the shank 120 of the presser foot. The presser bar is comparatively small in diameter and is subject to torsional twisting to a slight extent, but the rigid arm attached to the shank of the presser foot and cooperating with the bracket rigidly fixed 125 to the lower end of the needle head prevents any possible lateral movement of the presser foot about the axis of the presser bar. The bearing of the presser foot shank against the arm on the bracket prevents any possible lateral or turning 130 movements of the foot about the axis of the presser bar.

The bearing of the presser foot shank against the arm carried by the bracket prevents any possible turning or lateral movements of the presser 135 foot around the axis of the presser bar in a counter clockwise direction as viewed in Figure 4. The vibrations and strains incident to the oscillation of the trimming blade and the oscillation of the cover thread guide and thread laying hook 140 do not in any way disturb the alinement of the presser foot relative to the needle and the stitching mechanism. In this type of machine where the presser foot has a channel for directing the upturned edge portions of the fabric sections to 145 the trimming mechanism, and wherein the presser foot cooperates with other members in the abutting or lapping of the trimmed edge portions, it is very essential that the presser foot should be maintained in a fixed alined position with the 150

feed. This is accomplished by the devices above described.

It is obvious that minor changes in the details of construction and the arrangement of the parts 5 may be made without departing from the spirit of the invention as set forth in the appended claims.

Having thus described the invention, what we 10 claim as new and desire to secure by Letters Patent, is:

1. In a sewing machine the combination of a needle head, a presser foot having a guiding means for directing the upturned edge portions of fabric sections, a presser bar mounted in said needle head and carrying the presser foot, horizontally disposed trimming devices including a stationary member mounted on said presser foot, cross thread laying mechanism, a collar attached to the presser bar and carrying spaced arms, a fixed post 15 with which said arms make sliding contact for guiding the presser bar in its up and down movements, and means carried by the needle head and engaging the presser foot at spaced points for holding the presser foot from turning on the presser bar and the presser bar from turning in either direction while permitting said presser foot to move up and down with said presser bar.

2. In a sewing machine the combination of a needle head, a presser foot having a guiding means 30 for directing the upturned edge portions of fabric sections, a presser bar mounted in said needle head and carrying the presser foot, horizontally disposed trimming devices including a stationary member mounted on said presser foot, cross thread laying mechanism, a collar attached to the presser bar and carrying spaced arms, a fixed post 35 with which said spaced arms make sliding contact for guiding the presser bar in its up and down movements, a bracket rigidly attached to the under face of said needle head and having devices 40 for engaging the shank of the presser foot in front of and in rear of the presser bar for preventing said presser foot from turning in either direction during the trimming operation.

3. In a sewing machine the combination of a needle head, a presser foot having a guiding means 45 for directing the upturned edge portions of fabric sections, a presser bar mounted in said needle head and carrying the presser foot, horizontally disposed trimming devices including a stationary member mounted on said presser foot, cross 50 thread laying mechanism, and means carried by the needle head and engaging the presser foot in front of and in rear of the presser bar for holding said presser foot from turning in either 55 direction about the axis of the presser bar during the trimming operation.

4. In a sewing machine the combination of a needle head, a presser foot having a guiding means 60 for directing the upturned edge portions of fabric sections, a presser bar mounted in said needle head and carrying the presser foot, horizontally disposed trimming devices including a stationary member mounted on said presser foot, cross 65 thread laying mechanism, a bracket rigidly attached to the needle head and having an arm contacting with the presser foot in front of the presser bar, said presser foot having an arm contacting with said bracket in rear of the presser 70 bar.

5. In a sewing machine the combination of a needle head, a presser foot having a guiding means for directing the upturned edge portions of fabric sections, a presser bar mounted in said 75 needle head and carrying the presser foot, hori-

zontally disposed trimming devices including a stationary member mounted on said presser foot, cross thread laying mechanism, a bracket bolted to the under face of the needle head and depending therefrom, said bracket having a forwardly projecting arm provided with a flat vertical face adapted to engage the shank of the presser foot in front of the presser bar, and an arm carried by the shank of the presser foot and having a flat face adapted to engage said bracket in rear of the presser bar whereby said presser bar is held from turning movement while permitted to freely move vertically. 80

6. In a sewing machine, the combination of a needle head, a presser foot, horizontally disposed trimming devices including a stationary member mounted on the presser foot, a bracket depending from said needle head and having a free sliding contact with the presser foot in front of the presser bar, and means carried by the presser foot bar having a free vertical sliding contact with said bracket in rear of the presser bar. 85

7. In a sewing machine, the combination of a needle head, a presser foot, horizontally disposed trimming devices including a stationary member mounted on the presser foot, a bracket rigidly bolted to the under face of the needle head and projecting downwardly therefrom, said bracket having a forwardly projecting arm provided with a flat vertical face adapted to engage a flat face 100 on the presser foot, said presser foot having a rearwardly projecting arm provided with a flat face adapted to engage a flat vertical face on the bracket, said flat faces on the bracket and the presser foot being disposed so as to prevent the 105 presser foot from turning about the axis of the presser bar in either direction while permitting said presser foot to freely move vertically.

8. In a sewing machine the combination of a needle head, a presser foot having a guiding means 110 for directing the upturned edge portions of fabric sections, a presser bar mounted in said needle head and carrying the presser foot, horizontally disposed trimming devices including a stationary member mounted on the presser foot, 115 an actuating sleeve surrounding the presser bar and extending from a point within the needle head to a point below the needle head, an arm clamped to the sleeve below the needle head, a movable trimming member carried thereby, an arm attached to the sleeve at the upper end thereof and within the needle head for actuating the sleeve, a bearing sleeve carried by the needle head in which the actuating sleeve is mounted for oscillation, said bearing sleeve projecting into 120 the needle head and below the needle head and extending throughout the greater portion of the length of the actuating sleeve between said actuating arm and the arm at the lower end of the sleeve which actuates the trimming member. 125

9. In a sewing machine the combination of a needle head, a presser foot having a guiding means for directing the upturned edge portions of fabric sections, a presser bar mounted in said needle head and carrying the presser foot, horizontally disposed trimming devices including a stationary member mounted on the presser foot, an actuating sleeve surrounding the presser bar and extending from a point within the needle head to a point below the needle head, an arm clamped to the sleeve below the needle head, a movable trimming member carried thereby, an arm attached to the sleeve at the upper end thereof and within the needle head for actuating the sleeve, a bearing sleeve carried by the needle 130 head in which the actuating sleeve is mounted for oscillation, said bearing sleeve projecting into 135 the needle head and below the needle head and extending throughout the greater portion of the length of the actuating sleeve between said actuating arm and the arm at the lower end of the sleeve which actuates the trimming member.

head in which the actuating sleeve is mounted for oscillation, said bearing sleeve projecting into the needle head and below the needle head and extending throughout the greater portion of the 5 length of the actuating sleeve between said actuating arm and the arm at the lower end of the sleeve which actuates the trimming member, thread laying devices supported by the presser foot, and means carried at the lower end of said 10 actuating sleeve for imparting oscillating movements to the thread laying devices.

10. In a sewing machine, the combination of a needle head, a presser foot, horizontally disposed trimming devices including a stationary member 15 mounted on the presser foot, a bracket secured to the lower face of the needle head and engaging the presser foot at spaced points for holding said foot from turning about the axis of the presser bar in either direction during the trimming operation, and means for securing said 20

bracket to said needle head whereby it may be shifted laterally to different set positions.

11. In a sewing machine, the combination of a needle head, a presser foot, horizontally disposed trimming devices including a stationary member 80 mounted on the presser foot, a bracket secured to the lower face of the needle head and engaging the presser foot at spaced points for holding said foot from turning about the axis of the presser bar in either direction during the trimming operation, said bracket having bolt holes therethrough, bolts passing through said holes and threaded in said needle head, said bolt holes being so proportioned relative to the bolts as to permit said bracket to be shifted in any direction for taking up wear and for alining the pressure foot with the feeding and stitching elements. 85
